His Attorney.

UNITED STATES PATENT OFFICE

2,326,336

BASE FOR ELECTRIC LAMPS AND
SIMILAR DEVICES

Roscoe S. Dick, Conneaut, Ohio, assignor to General Electric Company, a corporation of New York

Application June 8, 1942, Serial No. 446,275

9 Claims. (Cl. 176—32)

This invention relates to bases for electrical devices such as lamps and discharge devices, and is especially useful for fluorescent lamps of the usual tubular positive column discharge type. The invention aims at simplifying and cheapening the bases and their manufacture, and at dispensing with the use of expensive insulating material (such as Bakelite or other plastic) that has been required in bases for fluorescent lamps as heretofore made. In suitable forms of embodiment, such as hereinafter described, the invention provides a simple and satisfactory base in which only a small amount of relatively inexpensive insulation is required. Various other features and advantages of the invention will become apparent from the description of species and forms of embodiment, and from the drawing.

In the drawing, Figs. 1 and 2 are tilted inside and outside views of a fluorescent lamp base embodying the invention, a portion of the skirt of the base being shown broken away in Fig. 2; Fig. 3 shows an axial section of the base applied to a lamp, which is shown in side elevation; and Fig. 4 is an exploded view of the parts of the base, which are shown tilted.

Fig. 5 is an outside end view of a modified base construction; Fig. 6 shows an axial section therethrough, taken as indicated by the line and arrows 6—6 in Fig. 5; Fig. 7 is a similar view illustrating a modification; and Fig. 8 is a similar view showing another modification.

Fig. 9 is a view similar to Fig. 4 illustrating yet another modification.

Figs. 10 and 11 are tilted views illustrating modified forms of the principal base parts; Fig. 12 is an outside end view of a base embodying the parts shown in Figs. 10 and 11; and Fig. 13 is a sectional view taken as indicated by the line and arrows 13—13 in Fig. 12.

Figs. 14 and 15 are views similar to Figs. 11 and 12 illustrating a simplified form of construction.

In general appearance, as shown in Figs. 1-4, my new terminal or base structure B resembles those now in common use, comprising a transverse wall or disc 20, which is the main structural element and carries the bipost contacts 21, 21 projecting outward from one side thereof, and also a shell or skirt 22 attached to the periphery of the disc 20 and projecting inward to the other side of the disc. Instead of being a separate insulative member, as usual, the disc 20 here shown is a sheet metal web integral with the shell or skirt 22, both these parts being of sheet metal. Such a sheet metal cup or pan structure is easily

formed by a die punching and drawing operation, out of thin gauge mild steel, which may be of 0.010 inch thickness. To provide for insulating the contact terminals or posts 21, 21 from the sheet metal and from each other, they are mounted on an insulative web structure 24 that coincides substantially with a flanged opening 25 (see Fig. 4) in the sheet metal wall or disc member 20. I have here and hereinafter referred to the member 20 as a disc, because of its circular outline as illustrated, though it will be understood that no particular outline for the member 20 is essential to my invention.

As here shown, the web 24 is double, comprising counterpart oblong, round-ended insulative plates 26, 27 at opposite sides of the disc 20. In forming a flanged edge for the opening 25, the margin of the disc 20 at the opening may be offset, joggled, or displaced laterally inward from the general plane of the disc 20 a distance about equal to the thickness of the outer plate 26, so as to form a rabbeted oblong seat 28 for this plate 26 and allow its outer surface to be about flush with that of the sheet metal disc. As shown in Figs. 1, 2, and 4, the disc 20 may be strengthened and stiffened by means of depressed (or inward-embossed) half-round ribs 29 extending substantially from its periphery to the flange or shoulder 30 around the seat 28. The plates 26, 27 are clamped together on the offset margin of sheet metal that forms the seat 28 by means of the hollow biposts 21, 21 riveted through both of them. Accordingly, the outer plate 26 is held seated by the inner plate 27 as a retaining means overlapping behind the flange 28, and is anti-turningly engaged in the oblong seat against the engagement means afforded by the flange 30, Figs. 3 and 4, that results from the offset conformation. When the base B is placed on one end of the lamp tube L, as shown in Fig. 3, after the application of ordinary basing cement 31, the lead wires 32, 32 from the cathode 33 are passed through the hollow biposts 21, 21, and are afterward soldered or welded into these posts and cut off, in the usual way. As shown in Figs. 2, 3, and 4, the inner plate 27 may have a central hole or recess 34 to accommodate the lamp exhaust tip 35 with sufficient clearance.

Other retaining means for holding the insulative plate 26 in the seat 28 are illustrated in Figs. 5 and 6. As here shown, the joggled conformation of the sheet metal around the seat 28 is interrupted at points near the ends of the seat at each side of the opening 25, where there are 55 retaining ears or lugs 36 of suitable width formed

of unoffset portions of the sheet metal of the disc 20. These ears 36 may initially be bent outward about at right angles to the disc 20, as shown in dot and dash lines in Fig. 6, to facilitate insertion of the insulative plate 26 in the seat 28, and then bent back against the outer surface of the plate 26 (flush with the disc 20, or nearly so) to hold the plate 26 securely in place in the seat. Located as shown near the ends of the plate 26 and the biposts 21, 21, the ears 36 are very effective in resisting any tendency of the plate 26 to twist askew, by mounting the edges of the seat, when torque is applied to the biposts in installing the lamp L or removing it. As shown at 37 in Fig. 7, the extreme inner ends of the lugs 36 may be bent and locked into corresponding indentations in the insulative plate 26. If the plate 26 is thick and stiff enough, the ears or lugs 36 may allow the inner plate 27 to be dispensed with altogether, as shown in Figs. 6 and 7; but if the plate 26 is thin or not so stiff, the inner plate 27 may be employed as well as the lugs or ears 36, as shown in Fig. 8, as an additional means of holding the plate 26 in the seat 28, besides providing greater stiffness.

The construction illustrated in Fig. 9 combines with the features of Figs. 1-4 the use of lugs or ears 36a, 36a extending inward from the edge of the rabbeted seat 28 at either end and engaged in notches 38, 38 in the ends of the inner plate 27a, so as to provide additional engagement against turning of both plates 26a, 27a, which are secured together by the biposts 21, 21.

Figs. 10-13 illustrate a modification in which the flanging and the rabbeted seat around the opening 25 are dispensed with—Fig. 10—and the rather thick, stiff insulative plate 26b has its edge flanged and rabbeted at 28b, Fig. 11, to seat against the sheet metal margin around the opening 25. At the opposite ends of the opening 25, there are lugs or ears 36b, 36b extending inward in notches 38b, 38b in the flange of the plate 26b, very much as in the case of the lugs 36a and notches 38 in Fig. 9, and thus providing additional engagement against turning of the plate. The ends 37b of the lugs 36b are bent over on the inner surface of the plate 26b, to hold it seated and antiturningly engaged as above described. The ears or lugs 36b may be formed as tongues of the sheet metal of the disc 20, left projecting into the opening 25 when the latter is punched, as shown in Fig. 10, and afterward bent up; or they may be bent up as shown in dot and dash lines in Fig. 13 by the final movement of the punching dies.

Figs. 14 and 15 illustrate a further modification which differs from Figs. 10-13 in that a plain, unrabbeted insulative plate 26c is seated against the plain, unrabbeted margin of the sheet metal disc 20 around the opening 25, and is held in place and antiturningly engaged solely by lugs or ears 36c engaged in end notches 38c of the insulative plate and bent over on its inner side at 37c, substantially as in Figs. 9-12. As shown in Fig. 14, the reinforcing ribs 29c extend diagonally instead of in line with the plate 26c and at right angles to it.

Throughout the drawing, homologous parts are marked with the same reference numerals in order to dispense with repetitive description, distinctive letters being added where such distinction of modified parts appears necessary.

It is apparent that the amount of insulating

material required for the plates 26, 26a, 26b, 26c, 27, 27a, 27d is much less than when the whole end wall or web of the base is of insulation, as is now usual. Furthermore, the insulation for these plates may consist of relatively inexpensive indurated fiber, as contrasted with the more costly and less available Bakelite or plastic hereunto used for the end walls of fluorescent lamp bases.

What I claim as new and desire to secure by Letters Patent of the United States is:

1. A base of the character described comprising a sheet metal disc, for mounting at the end of an envelope, said disc having therein an opening, an insulative plate laterally seated against said sheet metal disc over said opening, bipost contacts fixed in said insulative plate within said opening, and thus insulated from the sheet metal and from one another, engagement means on said sheet metal disc displaced laterally from the plane thereof and antiturningly engaged with said insulative plate, and means for holding said insulative plate to said sheet metal disc in engagement with its said engagement means as aforesaid.

2. A base of the character described comprising a sheet metal disc, for mounting at the end of an envelope, said disc having therein an opening, an insulative plate seated and antiturningly engaged in said opening, bipost contacts fixed in said insulative plate within said opening, and thus insulated from the sheet metal and from one another, and retaining means attached to said insulative plate overlapping the sheet metal disc at the other side thereof from the aforesaid insulative plate.

3. A base of the character described comprising a sheet metal disc, for mounting at the end of an envelope, said disc having therein an opening, an insulative plate over said opening laterally seated against the sheet metal of said disc and having notches in its margins, bipost contacts fixed in said insulative plate within said opening, and thus insulated from the sheet metal and from one another, and projections on said disc antiturningly engaged in said notches, with means for holding said insulative plate to said disc with the disc projections in the marginal plate notches as aforesaid.

4. A base of the character described comprising a sheet metal disc, for mounting at the end of an envelope, said disc having therein an opening, an insulative plate over said opening laterally seated against the sheet metal of said disc and having notches in its margins, bipost contacts fixed in said insulative plate within said opening, and thus insulated from the sheet metal and from one another, and lugs on said disc bent laterally therefrom and engaged in said notches, and also bent over on the plate margins to hold the plate to the disc.

5. A base of the character described comprising a sheet metal disc, for mounting at the end of an envelope, said disc having therein an opening with an offset margin forming a rabbeted seat, an insulative plate secured and antiturningly engaged in said rabbeted seat, and bipost contacts fixed in said insulative plate within said opening, and thus insulated from the sheet metal and from one another.

6. A base of the character described comprising a sheet metal disc, for mounting at the end of an envelope, said disc having therein an opening with an offset margin forming a rabbeted seat, an insulative plate antiturningly engaged

in said rabbeted seat, another insulative plate engaging said offset margin at the other side thereof, and bipost contacts riveted through said plates within said opening, whereby the first-mentioned plate is secured in said seat, while said bipost contacts are insulated from the sheet metal and from one another.

7. A base of the character described comprising a sheet metal disc, for mounting at the end of an envelope, said disc having therein an opening with an offset margin forming a rabbeted seat, an insulative plate antiturningly engaged in said rabbeted seat, retaining means on said sheet metal disc overlapping said insulative plate at the other side from the rabbeted seat, and bipost contacts fixed in said insulative plate within said opening, and thus insulated from the sheet metal and from one another.

8. A base of the character described comprising a sheet metal disc, for mounting at the end of an envelope, said disc having therein an opening with an offset margin forming a rabbeted seat, an insulative plate antiturningly engaged

in said rabbeted seat, another insulative plate engaging said offset margin at the other side thereof from the first-mentioned insulative plate, and secured to the latter, one of said plates having notches in its margins, and lugs on said disc bent laterally therefrom and engaged in said notches.

9. A base of the character described comprising a sheet metal disc, for mounting at the end of an envelope, said disc having therein an opening with an offset margin forming a rabbeted seat, an insulative plate antiturningly engaged in said rabbeted seat, retaining lug portions of the sheet metal of said metal disc overlapping said insulative plate at the other side thereof from the rabbeted seat, another insulative plate engaging said offset margin at the other side thereof from the first-mentioned insulative plate, and bipost contacts riveted through said plates within said opening, whereby the first-mentioned plate is secured in said seat, and yet said bipost contacts are insulated from the sheet metal and from one another.

ROSCOE S. DICK.
